UNITED STATES PATENT OFFICE.

RUDOLPH A. RIEK, OF RHINELANDER, WISCONSIN.

REFRIGERATOR.

1,111,496.

Specification of Letters Patent. Patented Sept. 22, 1914.

Application filed January 31, 1913. Serial No. 745,517.

To all whom it may concern:

Be it known that I, RUDOLPH A. RIEK, a citizen of the United States, residing at Rhinelander, in the county of Oneida and State of Wisconsin, have invented a new and useful Refrigerator, of which the following is a specification.

The present invention relates to refrigerators.

10 It is the primary object of the present invention to provide a novel and improved ice compartment or ice chest for a refrigerator, which may be removably supported by the front wall or door frame of the case, in order to eliminate the employment of obstructions, projections, recesses or grooves from or in the other walls of the refrigerator in or on which verdigris or other foreign matter might accumulate to render the interior of the refrigerator unsanitary.

25 A further object of the present invention is to provide a refrigerator having a doorway through which the ice chest is insertible, the ice chest being engageable with the edges 25 of the doorway or the door frame to be supported thereby, so that when the door is closed, the ice chest will be firmly locked in position, and in order that when the door is opened, the ice chest may be removed for 30 any purpose whatsoever.

With the foregoing general objects outlined, and with other objects in view, which will be manifest when the nature of the present invention is better understood, the 35 present invention resides in the combination and arrangement of parts and in the details of construction hereinafter described and claimed, it being understood that changes in the precise embodiment of invention herein disclosed can be made within the scope of what is claimed without departing from the spirit of the invention.

The invention has been illustrated in its preferred embodiment in the accompanying 45 drawings, wherein similar reference characters have been employed to denote corresponding parts and wherein:—

Figure 1 is a vertical section of the refrigerator taken through the ice chest. Fig. 50 2 is a horizontal section taken through the ice chest, and parts being broken away. Fig. 3 is an inverted perspective view of the auxiliary or false bottom for the ice chest. Fig. 4 is a sectional detail showing the manner for supporting the condensation pan 55 below the bottom of the ice chest. Fig. 5 is a perspective view of the ice chest with the false bottom removed. Fig. 6 is a sectional detail, and Figs. 7, 8 and 9 are fragmental details in perspective.

Referring specifically to the drawings, the refrigerator embodies a suitable case 10 containing a lining 11 of any suitable character, the lining being integral or of one piece. The particular construction of the case and lining need not be considered as the same are of no moment with reference to the present invention. The front of the case is preferably provided with suitable door frames, one of which provides a doorway 12 through which the ice compartment is adapted to be inserted, and which doorway is closed by the hinged door 13. The edges or frame of the doorway 12 are provided with a continuous outer rabbet providing a sea or shoulder 14, the door 13 being adapted to swing into the rabbet.

The ice chest or ice compartment has been designated generally by the numeral 15, the top and front of which are open. The ice chest embodies the open frame 16, comprising a pair of angle iron stiles 17 and a pair of angle iron rails 18 connecting the upper and lower ends of the stiles, the ends of the flanges of the respective stiles and rails being overlapped and riveted or otherwise secured together, so that the frame is substantial and simple in construction. Those flanges of the stiles and rails, which are outermost, are arranged in substantially the same plane, and have their ends overlapped and secured together. Thus, the ends of the outer flanges of the stiles overlap the outer sides of the ends of the outer flanges of the rails, whereby the inward pressure given to bear upon the stiles will be effectively resisted by the ends of the stiles bearing against the ends of the rails. The ends of the inner flanges of the rails are bent angularly to overlap the ends of the inner flanges of the stiles behind the outer flanges of the stiles, which will assist in resisting the inward pressure exerted upon the stiles, due to the weight of the ice within the chest, as will hereinafter more fully appear. Thus, the ends of the outer flanges of the stiles overlapping the outer sides of the ends of the outer flanges of the rails, and the ends of the inner flanges of the rails being bent angularly behind the outer flanges of the stiles will effectively

serve to brace the stiles in place, even though the rivets or securing members should be weakened by use or corrosion. This frame 16 is of such proportions as to fit snugly within the doorway 12, the outer flanges being adapted to seat or rest against the seat 14 with the other or inner flanges fitting within the smaller or inner portions of the doorway or door frame beyond the rabbet. A hand hold 19, preferably fashioned from wire, is pivoted to the upper stile 18, preferably by means of a doubled plate 20 having its ends riveted or otherwise secured on the inner flange of the upper rail and forming a loop through which the hand hold is passed. The doubled plate 20 forms a bearing member secured to the upper end or stile of the chest frame and projecting inward therefrom, the handle being pivoted to the inner end of the bearing member, to depend therefrom, or to be swung upwardly out of the way. This hand hold 19 ordinarily depends from the upper stile in order that it may be readily accessible through the doorway and through the frame 16, but may be swung upwardly out of the way when necessary or desirable. The door 13 is also provided with a contracted portion adapted to fit within the frame 16 when the door is closed. Thus, when the frame 16 is inserted into the doorway, and when the door is closed, the said frame 16 will be firmly held in position, and when the door is opened, the frame may be removed, which will permit of the removal of the ice chest, as will hereinafter appear. The ice chest also embodies the sides 21 and the back 22, which may be constructed of separate blanks of sheet metal or the like, beaded or otherwise secured together, or which may be bent from being bent or curled over said rod. The upper edges of the sides and back are preferably reinforced by a rod 23, the upper edges being bent or curled over said rod. The forward edges of the sides 21 are riveted or otherwise secured to the inner flanges of the stiles 17, and preferably to those faces of the said flanges remote from the center of the ice chest frame. The upper edges of the sides and back terminate in a horizontal plane substantially below the horizontal plane of the upper rail 18, and the sides and back are provided with the upper horizontal corrugations 24 and with the vertical corrugations 25 below the corrugations 24. These corrugations serve to prevent the ice from lying flatly against the sides and back of the ice compartment and thereby serve to prevent the ice from contacting with the greater surface of the sides and back so as to leave a gap or space between the ice and the adjoining walls, which is desirable. These corrugations also prevent objects from lying flatly against the outer faces of the sides and back, which is also desirable. These corrugations

not only serve for the purposes above indicated, but also serve to strengthen the sides and back against buckling, warping or other distortions.

The bottom of the ice chest has been designated by the numeral 26, the same having an upstanding peripheral flange 27 overlapping and secured to the sides 21 and the back 22, so that the bottom is in the form of a pan. The forward end of the bottom 75 or pan 26 is spaced from the front wall or door frame of the case, as will clearly be apparent by reference to Fig. 1, and a lip 28 projects from the upper edge of the front wall of the pan 26, this lip 28 being riveted 80 or otherwise secured to the bottom face of the inner flange of the lower rail 18. In the manner above described and depicted in the drawings, the sides, back and bottom are all firmly secured together and are rigidly secured to the frame 16, so that when the frame is supported within the doorway, the ice chest will be properly held within the case; the ice compartment or ice chest being accessible through the doorway or 90 opening 12. It is also to be noted that the bottom or pan 26 depends below the horizontal plane of the lower edge of the doorway 12, the front end of the pan terminating short of the front wall of the case or 95 door frame so as to permit the upper end of the frame 16 to swing outwardly, but to constrain the ice chest from being slid outwardly on the lower edge of the doorway.

In order to catch the condensation which 100 accumulates on the exterior of the ice chest, a condensation pan 29 is supported directly below the bottom 26 of the ice chest, the pan 29 having its sides or flanges 30 upstanding around the bottom 26 to catch the condensation as it runs downward and drips from the sides, back and bottom. The bottom or 105 pan 26 and the condensation or supplemental pan 29 are provided with the registering or complementary openings 31 and 110 32 respectively, which openings are preferably elliptical or elongated and which permit of the downward circulation of air into and through the provision chamber. The edges of the respective openings 31 and 32 115 are upturned into the respective flanges 33 and 34, which flanges prevent the drip water, and condensation from passing downwardly through the said openings. The condensation pan 29 is suspended from the 120 bottom or main pan 26 in a novel manner, a plurality of strips 35 being secured to the pan or flange 34 thereof around the opening 32 and being bent over the edge 33 of the bottom 26. In this manner, the condensation pan is not only supported from the bottom of the ice chest, but is also constrained and locked against movement, although the condensation pan may be readily moved by bending the strips or tongues 35 125 130

so that they may pass through the opening 31 of the bottom. The bottom 26 is provided with a depending nipple 36 at its rear end for permitting the discharge of drip water, the said nipple passing through an opening 37 in the condensation pan 29, and the edges of the said opening being downturned to provide a short nipple or flange 38 loosely surrounding the nipple 36 and 5 permitting the condensation to drip downwardly exteriorly of the nipple 36. An upstanding discharge tube or pipe 39 is connected to the usual trap, and the nipple 36 is adapted to extend slightly within the 10 upper end of the discharge tube 39, this tube or pipe 39 being adapted to receive both the condensation and drip water.

The auxiliary or false bottom has been designated by the numeral 40, the same being constructed of a corrugated sheet metal plate and having a plate 41 secured on its lower face, together with a pair of transverse bars 42, the terminals of which are bent downwardly into feet 43. This false bottom 40 is adapted to be supported above the bottom 26 of the ice chest, the feet 43 serving to support the false bottom above the bottom or pan 26, as well as above the flanges 33 and 34. The false bottom 40 is 20 disposed loosely within the ice chest, or the edges and end thereof are spaced from the sides and back of the ice chest, in order to permit of the circulation of air. It is upon the false bottom 40, that the ice is adapted 25 to rest, so that air may circulate through the openings 31 and 32 and around the false bottom.

In use, as above indicated, when the ice chest is disposed within the case, the frame 40 16 is adapted to fit within the doorway, so that the ice chest is supported solely from the door frame or from the wall of the case. In this manner, the employment of obstructions, projections, recesses or grooves 45 from or in the sides, back, top and bottom of the case will be eliminated, in order that the interior of the case may be smooth and free from crevices and protuberances in or upon which verdigris or other extraneous 50 matter might accumulate. As above noted, also, air may circulate vertically through the ice chest and around the ice, in order that the air may be cooled to the most effective degree, the waste or drip water being 55 readily discharged, and the condensation on the exterior of the ice chest being caught and discharged together with the waste or drip water. When it is desired to remove the ice chest for any reason whatsoever, 60 after the door 13 has been swung open, the upper end of the frame 16 may be swung outwardly slightly, thus withdrawing the nipple 36 from the discharge tube 39, and permitting the ice chest to be slightly elevated to bring the bottom thereof above the 65

lower end of the doorway, in which event, the ice chest may be drawn outwardly without interference. Conversely, the ice chest may be readily inserted into the case, it being noted that the weight of the ice chest 70 will tend to maintain the frame 16 in position within the doorway, so that the ice chest will be properly supported from the front wall or door frame.

The present ice chest is comparatively 75 simple, compact, substantial, durable, and inexpensive in construction, and is convenient, serviceable and efficient in its use. The ice chest may be readily removed from time to time for purposes of cleaning in order 80 that the ice chest may be maintained in the most sanitary or hygienic condition, it being also noted that the false bottom and condensation pan may be removed when necessary or desirable. This ice chest is not 85 only sanitary, but provides for a perfect circulation of air therethrough in order that the air may be retained in the most pure and cool condition possible.

What is claimed is:—

1. In a refrigerator, a case having a door frame in one upright wall provided with a continuous rabbet, an ice chest having its front open and insertible through the door frame and having an angle iron frame 90 adapted to seat in the said rabbet to support the ice chest, a bearing member secured to the upper end of the ice chest frame and projecting inward therefrom, and a handle pivoted to the inner end of the bearing member adapted to depend from the upper end of the ice chest frame or to be 95 swung upwardly out of the way.

2. In a refrigerator, a case having a door frame in one upright wall provided with a 105 continuous rabbet, an ice chest frame including angle iron stiles and rails having their outer flanges arranged in substantially the same plane and having their ends overlapped and secured together, the ends of 110 the inner flanges of the angle iron rails being bent angularly to overlap the ends of the inner flanges of the stiles and being secured thereto, the outer flanges seating in the rabbet and the inner flanges fitting in 115 the door frame beyond the rabbet, and an ice chest including sides and a bottom secured to the inner flanges of the stiles and lower rail, respectively.

3. In a refrigerator, a case having a door frame in one upright wall provided with a continuous outer rabbet, an ice chest frame including angle iron stiles and rails having their outer flanges arranged in substantially 120 the same plane, the said flanges of the stiles 125 having their ends overlapping and secured to the outer sides of the ends of the said flanges of the rails, the ends of the inner flanges of the rails being bent angularly to overlap the ends of the inner flanges of the 130

stiles behind the outer flanges of the stiles and being secured thereto, the outer flanges seating in the rabbet and the inner flanges fitting in the door frame beyond the rabbet, and an ice chest including sides and a bottom secured to those sides of the inner flanges of the stiles and lower rail, respectively, remote from the center of the ice chest frame.

In testimony that I claim the foregoing as my own, I have hereto affixed my signature in the presence of two witnesses.

RUDOLPH A. RIEK.
